UNITED STATES PATENT OFFICE.

HAROLD T. KINGSLEY, OF DETROIT, MICHIGAN.

MECHANICAL TOY.

Application filed March 16, 1922. Serial No. 544,289.

To all whom it may concern:

Be it known that I, HAROLD T. KINGSLEY, a citizen of the United States, residing at Detroit, in the county of Wayne and State 5 of Michigan, have invented certain new and useful Improvements in a Mechanical Toy, of which the following is a specification, reference being had to the accompanying drawings.

10 My invention relates to a mechanical toy and more particularly to a toy adapted to mechanically produce music.

It is one of the objects of my invention to provide such a device suitably housed 15 within a toy person so as to render the working parts thereof invisible when in operation.

It is a further object of my invention to provide such a device adapted to play a number of tunes and also to produce the 20 effect of a musician playing upon a musical instrument.

It is a further object of my invention to provide such a device of simple and compact structure and whereby the operation of the 25 same will be entirely automatic and continuous.

With these and other objects in view, my invention consists in the arrangement, combination and construction of the various 30 parts of my improved device as described in the specification, claimed in my claims and shown in the accompanying drawings, in which:

Fig. 1 is an elevation showing a toy person and a toy mechanical instrument being 35 played by said person.

Fig. 2 is a similar view showing the operation and construction of the arm on the toy person.

40 Fig. 3 is a sectional view of the toy person showing in elevation the operating mechanism mounted therein.

Fig. 4 is a top or plan view of the said 45 operating mechanism.

Fig. 5 is a rear view of the same.

Fig. 6 is a side elevation of the same.

Fig. 7 is a view looking upwardly from the bottom of the said mechanism.

Fig. 8 is a view taken on line 8—8 of 50 Fig. 3.

I have shown a toy musician 1, supporting with his left hand 2 a trombone 3 held at the mouth 4 of the musician.

55 I have shown the musician 1, as standing upon a block 5 and I provide a brace or support 6 having variations 7 and 8 there-

in and extending through the body of the musician so as to strengthen the same. The brace 6 is provided with screw threads 9 on its lower end and a nut 10 is screwed 60 thereon so as to hold the same firmly in place.

Protruding through the back 11 of the musician is a shaft 12 having a key 13 on one end thereof and extending through a 65 bearing 14 to the inside of the musician. The inner end thereof is provided with a gear 15 meshing with a gear 16 on the end of the shaft 17 which shaft extends to and operably connects with a coil spring 18 supported on a mounting 19 so that rotation of the key 13 will cause the spring 18 to be coiled.

Also mounted on the shaft 17 is a gear 20 adapted to be rotated by the uncoiling 70 of the spring 18 and meshing with a gear 21 on the shaft 22. The outer end of the shaft 22 is provided with a wheel 23 to which is connected at 24 a rod 25, which rod 25 is connected at its opposite end to a bellows 26 so that uncoiling of the spring 18 will cause rotation of the wheel 23 and pitman like movement of the rod 25 thus opening and closing the bellows 26 so as to produce a current of air thereby. This current of 75 air passes out of the bellows at 27 through a tube or hose connection 28 into the container or valve housing 29 within which are located a series of valves 30 the alternate 80 opening and closing of which will alternately permit the passage of the air therethrough so as to produce musical notes. The valves 30 are of old and well known construction including in their structure the customary reeds, and are not here described 85 in detail.

The musical notes thus produced by the passage of air through the valves 30 will pass therefrom into the container 99 through 90 a tube or hose connection 31 into the trombone 3, at 32 and out through the flared portion 33 thereof.

In order to give the notes passing through the trombone 3 a "trombone effect," I have provided a pair of plates 93 in the passage-way of the trombone having a series of perforations 34 therein. Between the said plates 93, I interpose 2 or 3 sheets of relatively thin paper as illustrated by the numeral 35. This will cause the music issuing 100 from the trombone to have a natural sound 105.

In order to control the valves 30 and cer-

respondingly the musical notes emitted therethrough, I have provided a gear 36 mounted on the shaft 37 and adapted to mesh with a gear 38 on the shaft 17. Also 5 provided on the shaft 37 is a gear 39 adapted to mesh with the gear 40 on the shaft 41. The shaft 41 is operably connected at one end with a cylinder 42 so that uncoiling of the spring 18 will cause movement through 10 the shaft 17, the gears 38, 39 and 40 through the shaft 41 to the cylinder 42 thereby causing the said cylinder to rotate.

The cylinder 42 is provided with a series of projections 43 thereon adapted to engage 15 prongs 44 on the ends of the rocker arms 45 which arms are adapted to rock on pivots 46. Certain of the rocker arms 45 are provided with heads 47 to act upon the valves 30 and others are adapted to be attached as 20 at 48 to rod 49 and at 50 to rod 51 as is more particularly shown in Figs. 1, 5 and 6.

It will thus be seen that the projections 25 43 on the cylinder 42 will control through the heads 47 the opening and closing of the valves 30 and may be so arranged as to cause the proper valves to open at specified times so as to produce the proper sequences of musical notes in the production of a musical tone.

30 The rod 49 attached to one of the rocker arms 45 is connected through a series of jointed arms or rods 52, 53, and 54, said latter arm being pivoted as at 97 to a wire or similar connection 55 passing over a 35 roller 71 secured within the body of the musician and leading to the slide portion 56 of the trombone so that rotation of the cylinder 42 and connection of the projections 43 thereon with the prongs 44 will cause 40 movement of the said arms 49, 52, and 54 and the slide portion 56 to be drawn inwardly on the portion 57 of the trombone. A spring 58 provided in the said trombone and bearing against the portion 57 will 45 cause the outward movement of the said portion 56 when the inward pressure thereon is released thus giving a reciprocating motion thereto as happens with real trombones.

50 The hand 59 of the musician will follow the portion 56 of the trombone as is shown by the dotted lines in Fig. 1 by reason of the arm of the musician being made in two portions 60 and 61 and pivoted at 62 and 63. 55 As will be seen in Fig. 2, the portion 60 of the musician's arm is encased within the portion 61 thereof so that when the arm is straightened, the portion 60 may recede within the portion 61.

60 The rod or arm 51 attached to one of the rocker arms 45 is connected through the V shaped rod or arm 64 to a wire or other similar connection 65 and leading over the rollers 66 and 67 secured within the body 65 of the musician to a connection 68 on the

foot 69 of the musician. The foot 69 is pivoted to the block 5 as at 70 so that reciprocation of the rocker arm 45 caused by the projections 43 will cause reciprocating movement through the arms or rods 51 and 70 64 and the wire 65 to the foot 69 causing the foot to be raised and lowered as shown in Fig. 1, the weight of the foot allowing downward movement thereof when the upward pressure of the wire 65 is released. 75

In order to secure the above mentioned mechanisms within the musician 1, I have provided a bar 72 fastened to the inner side of the musician and being bent to form a portion 73 so as to form a supporting arm 80 in which the shaft 41 is journaled at one end at 74 and to which the container 29 is secured as at 75. I also provide a member 76 having an arm 77 extending therefrom and in which the opposite end of the shaft 85 41 is journaled as at 78 and to which the container 29 may be secured as at 79. These two members 72 and 76 form the main support for the entire operating mechanism within the musician.

It will thus be seen that I have provided a compact and complete toy adapted to automatically perform the motions of a trombone player and to produce musical tones. I wish it understood that the projections 43 95 on the cylinder 42 may be varied so as to produce an assortment of musical tones and that the gearing mechanisms operating the bellows 26 and the cylinder 42 may be arranged as desired in so far as sizes are concerned in order to regulate the speed at which the various mechanisms shall operate according to the desires of the maker or user.

It is obvious that various changes may 105 be made in the arrangement, combination and construction of the various parts of my improved device without departing from the spirit of the invention therein and it is my intention to cover by my claims such changes 110 as may be reasonably included within the scope thereof.

What I claim is:

1. In combination, a toy person, having 115 encased therein a bellows, a cylinder and a valve housing, said housing containing a plurality of air chambers having reed blocks and valves for operating the same, spring mechanisms adapted to operate said bellows for forcing air into said housing and valves and to operate said cylinder and operating arms connecting said cylinder and valves, adapted on movement of said cylinder to regulate the opening and closing of said valves. 120

2. In combination, a toy person, having 125 encased therein a bellows, a cylinder and a valve housing, said housing containing a plurality of air chambers having reed blocks and valves for operating the same, spring 130 mechanisms adapted to operate said bellows for forcing air into said housing and valves and to operate said cylinder and operating arms connecting said cylinder and valves, adapted on movement of said cylinder to regulate the opening and closing of said valves.

- mechanisms adapted to operate said bellows for forcing air into said housing and said valves and to rotate said cylinder, the cylinder having a plurality of projections thereon, and rocker arms connected with and extending over said valves and said cylinder, adapted to be actuated by said projections on the cylinder and when so operated to alternately open and close said valves.
- 10 3. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves and to operate said cylinder and operating arms connecting said cylinder and valves, adapted on movement of said cylinder to regulate the opening and closing of said valves and means leading from said valve housing for carrying the sound produced by said valves to a toy musical instrument held by said toy person.
- 15 4. In combination, a toy person, having encased therein a bellows, a cylinder and a valve housing, said housing containing a plurality of air chambers having reed blocks and valve for operating the same, spring mechanisms adapted to operate said bellows for forcing air into said housing and valves and to operate said cylinder, and operating arms connecting said cylinder and valves adapted on movement of said cylinder to regulate the opening and closing of said valves and means leading from said valve housing for carrying the sound produced by said valves to a toy musical instrument held by said toy person.
- 20 5. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves and to operate said cylinder, and operating arms connecting said cylinder and valves adapted on movement of said cylinder to regulate the opening and closing of said valves, said toy person having a hinged foot thereon, and further operating arms operated by the cylinder and adapted to actuate said foot.
- 25 6. In combination, a toy person, having encased therein a bellows, a cylinder and a valve housing, said valve housing containing a plurality of air chambers having reed blocks and valves for operating the same, spring mechanisms adapted to operate said bellows for forcing air into said housing and valves and to operate said cylinder, and operating arms connecting said cylinder and valves adapted on movement of said cylinder to regulate the opening and closing of said valves, said toy person having a hinged foot thereon, a toy musical instrument having a slide member thereon supported by said toy person, and further operating arms operated by the cylinder and adapted to simultaneously actuate both said foot and said slide.
- 30 7. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves and to operate said cylinder, and operating arms connecting said cylinder and valves adapted on movement of said cylinder to regulate the opening and closing of said valves, said toy person having a hinged foot thereon, a toy musical instrument having a slide member held by said toy person, and further operating arms operated by the cylinder and adapted to actuate said slide.
- 35 8. In combination, a toy person, having encased therein a bellows, a cylinder and a valve housing, said valve housing containing a plurality of air chambers having reed blocks and valves for operating the same, spring mechanisms adapted to operate said bellows for forcing air into said housing and valves and to operate said cylinder, and operating arms connecting said cylinder and valves adapted on movement of said cylinder to regulate the opening and closing of said valves, said toy person having a hinged foot thereon, a toy musical instrument having a slide member thereon supported by said toy person, and further operating arms operated by the cylinder and adapted to simultaneously actuate both said foot and said slide.
- 40 9. In combination, a toy person having encased therein a valve housing containing a plurality of reed chambers and valves for operating the same, spring mechanisms adapted to operate a bellows for forcing air into said housing and said chambers and to operate a cylinder having means thereon for regulating the opening and closing of said valves, said toy person having a hinged foot thereon and also supporting a toy musical instrument having a sliding member thereon, both said hinged foot and said slideable member being adapted to be actuated by similar regulating means on said cylinder.
- 45 5. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves,
- 50 6. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves,
- 55 7. In combination, a toy person, having encased therein a bellows, a cylinder and a valve housing, said housing containing a plurality of air chambers having reed blocks and valves for operating the same, spring mechanisms adapted to operate said bellows for forcing air into said housing and valves,

HAROLD T. KINGSLEY.
